(57) **CLAIM**

The ornamental design for an utility tower as shown and described.

DESCRIPTION

FIG. 1 is a perspective view thereof of a first embodiment for a utility tower showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment for a utility tower showing our new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken line showing is included for the purpose of illustrating the utility tower and forms no part of the claimed design.
